UNITED STATES PATENT OFFICE.

ANDREW DEVORE, OF NEW YORK, N. Y.

INDESTRUCTIBLE GOLD-LEAF CHARACTER AND METHOD FOR PREPARING THE SAME.

1,417,596.

Specification of Letters Patent. Patented May 30, 1922.

No Drawing.

Application filed November 29, 1920. Serial No. 427,014.

To all whom it may concern:

Be it known that I, ANDREW DEVORE, a citizen of the United States of America, residing at New York, in the county of New York and State of New York, have invented new and useful Improvements in Indestructible Gold-Leaf Characters and Method for Preparing the Same, of which the following is a specification.

10 The object of the invention, as its name implies, is to provide a letter or character made from gold leaf but of a character which will permit its being stamped from a sheet of the prepared material, whereby 15 the desired letters may be cut and pasted on a window or other place where it is desired they be used.

In preparing the material, a very thin sheet of transparent celluloid is treated on 20 one side with a sizing substance, preferably distilled water and pure gelatine, in the portions by bulk of eighty-five to ninety per cent water and ten to fifteen per cent gelatine. The gold leaf is applied to the sizing 25 while the latter is still wet. This is then allowed to dry after which the sheet is given a quick bath in hot water to which there is added a few drops of chloroform.

After the sheet dries from the results of 30 the above, a coat of varnish is applied on top of the gold leaf to protect the same in handling.

This method results in the production of 35 practically an indestructible character after the same is cemented to a glass or other surface and the letter or character will have practically an unlimited life. Signs produced by such characters can be made up cheaper and quicker as the letters can be cut

out with dies and can be applied on windows 40 by inexperienced persons in a fraction of the time that it requires by the old method of hand painting.

The provision of a sheet from which the desired letters can be stamped also makes 45 for economy in the use of gold leaf, as the trimming from large letters can be utilized to make smaller sized letters and what is left after cutting the smaller sized letters may be easily saved and melted together. While 50 the sheet materially comprises a layer of celluloid, a layer of sizing consisting of gelatine and water, a layer of gold leaf and a layer of varnish, the whole does not measure in thickness more than five-one-thou- 55 sandths of an inch.

Having described the invention what is claimed as new and useful is:-

1. The process for the production of an indestructible character which consists in 60 treating a sheet of celluloid with a sizing, then applying gold leaf to the sizing while wet, then giving the sheet a quick bath in hot water, and finally applying a protective coating on top of the gold leaf. 65

2. The process for the production of an indestructible character which consists in applying to a sheet of celluloid a sizing consisting of gelatine and water in the proportions to provide an adhesive, then applying gold leaf to the sizing while wet, then giving the sheet a quick bath in hot water containing a small percentage of chloroform, and finally, when the sheet is dry, applying a protective coating of varnish on the gold leaf. 70 75

In testimony whereof he affixes his signature.

ANDREW DEVORE.
